UNITED STATES PATENT OFFICE.

JOSEPH NIEBERDING, OF BALTIMORE, MARYLAND.

DOCKING APPLIANCE.

1,390,056.

Specification of Letters Patent.

Patented Sept. 6, 1921.

Application filed September 14, 1920. Serial No. 410,183.

To all whom it may concern:

Be it known that I, JOSEPH NIEBERDING, a citizen of the United States, residing at Baltimore city, in the State of Maryland, have invented a new and useful Docking Appliance, of which the following is a specification.

My invention relates to docking appliances and has for its object the providing of improved means of cleaning vessels while being docked.

A further object of my invention is the providing of improved staging and means of handling the same in dry dock operations.

With the foregoing and other objects in view, my invention consists of the novel construction, combination and arrangement of parts as hereinafter specifically described and illustrated in the accompanying drawing, wherein is shown the preferred embodiment of my invention, but it is understood that changes, variations and modifications may be resorted to which come within the scope of the claims hereunto appended.

In the drawing of the herein described embodiment of my invention, Figure 1 shows an outline view in elevation of a floating dry dock with a vessel on the same and my improved docking appliance in position for cleaning or painting the vessel. Fig. 2, is a plan view of one section of the staging, and Fig. 3, is a view in elevation of one section of the staging.

Similar numerals refer to similar parts throughout the several views.

In docking a vessel or hauling her out on a railway, it is desirable to provide means to enable the men in cleaning the vessel to be at about the surface of the water as the same lowers on the side of the vessel. Sometimes this is accomplished in a crude way by rafts or floats. After the vessel is docked or hauled out on a railway, trestles or other supports are brought into place and a staging built to enable the men to clean or paint the vessel's bottom. This is clumsy and costly.

1, is an outline section of a floating dry dock, but so far as my invention goes, it might be an outline section of the cradle of a railway, as the relative position of the vessel and my improved docking appliance would be the same in either case. 2, is a vessel docked or being docked. 3, is a staging derrick pivoted or hinged at 4 near the side of the dock or cradle and arranged to

swing up to the side of the dock or cradle or out against a vessel. 5, is a derrick tackle for handling the derrick. 6, is a staging handled from near the end of the derrick by 60 block and falls 7. Staging 6 is provided with guard rail 8.

Stagings 6 may be of any convenient length; in large docks 30 foot lengths have been found convenient. The derricks 3 are 65 conveniently placed along the dock to handle the staging. Derricks 3 are of sufficient length ordinarily to support the staging above the water level when the dock or cradle is submerged to its greatest depth required by the vessel to be docked when the derrick is resting against the side of the vessel after the vessel has taken the keel blocks.

It has been found that the derrick may conveniently be made of pipe provided with 75 a hinge or swivel at its lower end and curved and provided with wood fender 9 at its upper end, and near its upper end having link 10 to support block and falls 7 and connection 11 to attach derrick tackle 5. Derrick 80 tackle 5 is most conveniently handled from on top of the sides of the dock. Block and falls 7 may be lowered away as the water recedes, by the men working on the staging.

I have not attempted to minutely describe 85 the dock, blocking, etc., as that is old and well known, and the drawing amply illustrates the same.

In this specification and claims, when the term "dock" is used, the appliance upon 90 which the vessel rests while being taken out of the water is meant, and may consist of a floating dry dock, a marine railway cradle or a graven dock in which the vessel rests and the water pumped out, and when the 95 term "docking" is used it is meant the relative position of the vessel and the surface of the water relatively lowering.

Having thus described my invention, what I claim and desire to secure by Letters Patent is—

1. In a docking appliance, the combination of a member, means for pivoting one end of the said member to the floor of a dock, means operable from the top of the 105 dock wall to adjust said member relative to a member being docked, a staging suspended from the upper end of said member and means operable from said staging for adjusting the vertical position thereof. 110

2. In a docking appliance, the combination of a member, means for pivoting one

end of the said member to a submergible part of a dock between the maximum point of submersion at the side and the object being docked, means operable from the top of the dock wall to adjust said member relative to a member being docked, a staging suspended from the upper end of said mem-

ber and means operable from said staging for adjusting the vertical position thereof.

JOSEPH NIEBERDING.
